UNITED STATES PATENT OFFICE.

CHARLES J. VAN DEPOELE, OF LYNN, MASSACHUSETTS.

HOOKED SUSPENDER FOR ELECTRIC-RAILWAY CONDUCTORS.

SPECIFICATION forming part of Letters Patent No. 396,311, dated January 15, 1889.

Application filed November 7, 1888. Serial No. 290,176. (No model.)

To all whom it may concern:

Be it known that I, CHARLES J. VAN DEPOELE, a citizen of the United States, residing at Lynn, in the county of Essex, State of Massachusetts, have invented certain new and useful Improvements in Hooked Suspenders for Electric-Railway Conductors, of which the following is a description.

My invention relates to electric railways of that class in which the current is supplied from an overhead conductor, and the subject of the present application is an improved device for suspending such conductors.

The invention is a continuation of and improvement upon the conductor-suspending device shown in an application filed by me in the United States Patent Office on the 22d day of August, 1888, Serial No. 283,445; and its object is to provide a simple and effective device for the purpose above mentioned, and which is peculiarly adapted to support conductors when it is necessary to curve them—as, for instance, where they pass around the corners of streets.

The invention therefore consists in the details of construction and arrangement of parts whereby I am enabled to accomplish the object stated.

In the accompanying drawings, Figure 1 is a perspective view of my invention, showing the suspender as permanently secured to the ear which sustains the conductor. Fig. 2 is a side elevation of the suspender, showing it as made integral with the ear. Fig. 3 is a plan view of Fig. 2. Fig. 4 is a front elevation of Fig. 3. Fig. 5 is a side elevation of the suspender, showing it as detachably secured to the ear. Fig. 6 is a front elevation, and Fig. 7 a plan view, of the device shown in Fig. 5. Fig. 8 shows a different form of conductor-suspending device to which my invention is applied.

In the drawings, A is the overhead conductor, and B an ear having a bail formed on its central portion and tapering toward its extremities. The ear is formed with a groove, within which the conductor is brazed, soldered, or otherwise secured.

C is a metallic hook desirably formed by casting. The hook C is in the form of half of an arch, and may be curved, as shown in

the drawings. To one end of the hook C is attached the cross-wire a, secured to suitable supports (not shown) along the line of way. This hook C being in the form of a half-arch, 55 the end opposite that to which the cross-wire a is attached extends downward, and is adapted for attachment to the ear upon which the conductor is secured. This vertical portion of the hook is preferably made to lap over the upper part of the ear B, as shown in Fig. 1, and is secured thereto, thus affording a firm support for the conductor. It will be understood, however, that I do not limit myself to the vertical portion overlapping the 60 ear, as it may be merely attached thereto without overlapping, though the construction will not then be as strong.

In Fig. 1 the vertical portion of the hooked suspender is shown as riveted to the ear, thus affording a permanent support therefor. In Figs. 2, 3, and 4, however, the metallic suspender is shown as made integral with the ear B. This construction is desirable on account of its being cheaper to manufacture and less liable to subsequent derangement. Figs. 5, 6, and 7 show the same general form of parts illustrated in the previous figures except that the metallic hook C is detachably secured to the ear B by means of a bolt, b, 70 passing through the bent portion of the hook and the ear. Such a construction is desirable under some circumstances, though as a general thing the form illustrated in Figs. 2 and 3 is preferable. In Fig. 8 another mode of 75 supporting the conductor where the same is curved is shown. In this case a bar or rod, as D, is provided, to which the ears supporting the conductor are secured, and the metallic hook C is then secured in any one of the 80 ways before referred to to the bar or rod, thus dispensing with a number of the metallic hooks and making a very smooth neat curve or portion of a curve.

The main feature of novelty in my present 95 invention is embraced in a construction comprising a curved or hook-shaped suspending device adapted to be attached to a cross-wire or similar support and to an ear or bail upon the conductor, or directly to the conductor from one side, so that a grooved contact-wheel 100 passing along in contact with the under side

of the conductor can pass under the curve of the suspender, and the conductor can, when on a curve, be sustained from a number of transverse supporting-wires arranged on the outside of the curve.

5. I claim as my invention—

1. A suspending device for electric conductors, consisting of a metallic hook having a downwardly-extended part adapted for attachment to a conductor to be supported and a laterally-extending supporting wire or cable connected to the hook, substantially as described.

15. 2. The combination, with a suitable conductor, of a suspending device therefor, comprising a metallic hook provided with a downwardly-extending part adapted to engage and be attached to the conductor to be supported, and an arched portion extending laterally therefrom and downward into the plane of its support, and a laterally-extending supporting wire or cable connected to the hook, substantially as described.

20. 3. In combination with a suitable con-

ductor and a supporting-ear attached thereto, 25 a suspender device therefor, consisting of a metallic hook having a downwardly-extending part adapted for attachment to said ear, substantially as described.

4. In combination with a suitable conductor and a supporting-ear attached thereto, 30 a suspending device therefor, consisting of a metallic hook having a downwardly-extending part detachably secured to said ear, substantially as described.

5. In combination with a suitable conductor and a supporting ear or ears attached thereto, a suspending device therefor, consisting of a metallic hook having a downwardly and laterally extending part connected to said 35 ear or ears, substantially as described.

40. In testimony whereof I hereto affix my signature in presence of two witnesses.

CHARLES J. VAN DEPOELE.
